UNITED STATES PATENT OFFICE.

CHARLES E. DATH, OF CHICAGO, ILLINOIS, ASSIGNOR TO WILLIAM H. MINER, OF CHAZY, NEW YORK.

DRAFT-RIGGING YOKE.

1,285,951.

Specification of Letters Patent. Patented Nov. 26, 1918.

Application filed January 26, 1916, Serial No. 74,309. Renewed November 2, 1917. Serial No. 199,982.

To all whom it may concern:

Be it known that I, CHARLES E. DATH, a citizen of the United States, residing at Chicago, in the county of Cook and State of Illinois, have invented a certain new and useful Improvement in Draft-Rigging Yokes, of which the following is a full, clear, concise, and exact description, reference being had to the accompanying drawings, forming a part of this specification.

This invention relates to improvements in draft rigging yokes.

For many years railroads and railroad supply manufacturers have been desirous of providing a yoke and draw bar connection, wherein the latter may be readily detached without dropping the draft gear or yoke and having the parts so arranged that the attaching means are suitable for use with any standard draw bar whether the same is provided with a coupler key slot or not, and wherein slotting of the sills is avoided. As is well known, detachable draw bar and yoke connections are being used more and more by railroads and difficulty has been experienced in providing a draw bar and yoke connection which is attachable to old types of draw bars, since it is found that many old draw bars now in service are not provided with a coupler key slot. Furthermore, many of the railroads object to having the draft sills slotted for the reception of a coupler key or other locking member, inasmuch as the sills are weakened in proportion to the amount of metal cut away for the slots.

The object of my invention is to provide a yoke having simple and efficient means for detachably and readily connecting the same with a draw bar of any standard type, whether provided with a coupler key slot or not; which will avoid the slotting of sills; and which have the parts so arranged that the locking members are readily accessible.

The invention furthermore consists in the improvements in the parts and devices and in the novel combinations of the parts and devices herein shown, described or claimed.

In the drawing forming a part of this specification, Figure 1 is a part side elevation, part vertical section of a yoke and draw bar showing my improvements in connection therewith, Fig. 2 is a horizontal, longitudinal section taken substantially on the line 2-2 of Fig. 1. Fig. 3 is a front end elevation of the improved yoke. Fig. 4 is a detail

perspective of the locking block employed with my improvements. And Fig. 5 is a vertical, sectional view of a portion of a draft rigging showing my improvements employed with a yoke adapted to be used with a single 60 spring gear or friction draft gear.

In said drawing, and referring to the structure illustrated in Figs. 1 to 4, A designates generally a cast steel yoke of tandem design having an upper arm 10, lower arm 11, rear member 12, and integral hollow central thimble or post 13. At its front end, the yoke A is provided with a substantially rectangular hollow hood or head having an upper wall 14, side walls 15-15, and a lower, 70 transversely extending bridge or connecting piece 16. At its upper end, the hood or head is provided with a transversely extending front gib or shoulder 17 and a rear transversely extending gib or shoulder 18 adapted 75 to engage the front and rear shoulders of the draw bar butt 19. At its lower end, the hood of the yoke is provided with an upstanding gib or shoulder 20 against which the rear face of the draw bar butt engages under buff. 80 To support the draw bar butt in proper position and to lock it in place, I have provided a detachable and removable locking block 21, the latter at its rear end being provided with a downwardly extended gib or shoulder 22 adapted to be seated within a correspondingly formed groove or recess 23 in the hood of the yoke. At its front end, the lock block 21 is provided with an upstanding gib or shoulder 24 arranged to engage the lower 90 front shoulder of the draw bar butt. Said block 21 is also provided with a depending flange 25 which fits against the inner face of the bridge 16 and is adapted to be bolted thereto as by bolts 26-26. I also provide an 95 angle plate 27 arranged as most clearly shown in Fig. 1, said plate 27 having its upper flange extended rearwardly and seated within a transversely extending slot 28, formed in the front face of the block 21, whereby the angle plate 27 assists in supporting the block 21 in position. The hood of the yoke is also provided with shoulders 29-29 on the inner faces of the side walls thereof just above the bridge 16, said shoulders having their rear faces curved to correspond with the curved front face 30 of the gib or shoulder 24. The block 21 is also rounded at its rear end as indicated at 31, in order to facilitate insertion of the block 21, 100 105 110

and also to act as a cam for riveting the draw bar butt during the assembling operation.

All the parts are shown in the drawing as in normal position, and in order to remove the draw bar at any time, the bolts 26 are first removed, then the angle plate 27, whereupon the block 21 may be swung downwardly, the rear end of the block forming a pivotal connection with the adjacent part of the yoke. When the block 21 is removed, the draw bar butt may then be lowered sufficiently for the upper shoulder thereof to clear the gib 17, whereupon the draw bar 15 may be pulled out. The parts are assembled by steps the reverse of those above described, as will be understood.

In buff, the draw-bar butt will engage the shoulders 18 and 20 and thereby force the 20 yoke rearwardly to actuate the tandem gears. In draft, the draw bar butt will engage the gibs or shoulders 17 and 24 and in this connection, it will be noted that the shoulder 24 is rigidly braced by the inwardly extending shoulders 29, the block 21 as an entirety being also braced by engagement with the bridge 16 and flange 32.

In the yoke illustrated in Fig. 5, the arrangement is the same as that illustrated in 30 the other figures except that the gibs or shoulders 18 and 20 of the yoke shown in Fig. 1 are omitted, so that upon buff or inward movement of the draw bar, the latter will engage directly the front follower of the 35 gear and may slide inwardly independently of the yoke.

From the preceding description, it will be seen that the draw bar and yoke connection which I have provided is adapted for all 40 standard types of draw bars, the draw bar may be replaced or removed without disturbing the gear or the yoke, no slotting of the sills is necessary, and all the parts are readily accessible from beneath the draft rigging 45 even though the draft sills may extend down below the lower part of the yoke.

Although I have herein shown and described what I now consider the preferred method of carrying out my invention, the 50 same is merely illustrative and I contemplate all such changes and modifications that come within the scope of the claims appended hereto.

I claim:

55 1. A yoke for draft riggings having a hood at its forward end within which to receive the butt of a draw bar, means for engaging the upper part of the draw bar butt, a locking block adapted to engage the lower 60 front shoulder of the draw bar butt, said block being removable from below, and means formed integrally with said yoke for directly supporting the rear end of said block when the latter is in operative position.

2. A yoke for draft riggings having means at its front end to engage the upper portion of a draw bar butt, and a block associated with said yoke, said block being removable from the under side of the yoke, said yoke 70 being provided with shoulders against which said block bears on its front face under draft.

3. A yoke for draft riggings having a hooded forward end, and a removable locking block, said block having an upstanding gib at its front end to engage the draw bar butt and a depending gib at its rear end, said depending gib being normally seated in a recess provided therefor in the hood. 80

4. A yoke for draft riggings having a hollow head at its front end and an opening in the bottom thereof, and a removable locking block insertable through said opening and having an upstanding gib adapted to 85 engage the lower shoulder of the draw bar butt, said hood being provided on the inner faces of the side walls thereof with shoulders against which said gib is adapted to bear under draft. 90

5. A yoke for draft riggings having a hooded forward end with an opening at the bottom and a connecting bridge between the side walls thereof, a locking block removable through said opening and having an upstanding gib to engage the draw bar butt, and means for supporting said block in operative position, said means including a removable transversely extending plate supported on said bridge and engageable in a 100 slot in the front end of said block.

6. A yoke for draft riggings having a hollow head at the front end thereof, and a removable locking block, said block having an upstanding gib at its front end and a curved 105 rear end to facilitate insertion of the block and lifting of the draw bar butt, and detachable means for supporting the front end of said block in operative position.

7. A cast yoke for draft riggings having a 110 hooded forward end, said yoke being provided with a transverse gib to engage the upper shoulder of a draw bar butt, a locking block removable through an opening in the bottom of said hood, said block having an 115 upstanding gib to engage the lower front shoulder of a draw bar butt, a bridge extending between the side walls of the hood at the lower front end thereof, and an angle plate supported on said bridge, said plate having 120 a portion thereof extended into a slot on the front face of said block, and means for holding said block and angle plate in position.

8. A keyless yoke having a hooded forward end provided with an integral transversely extending shoulder across the upper portion thereof, the bottom wall of said hooded end having an opening there-through, a shouldered locking block insertible through said opening, integral abut- 125 130

ments formed on the inner faces of the side walls of the hood and against which said locking block is adapted to bear, and a removable key for supporting and retaining 5 said block in place.

9. A yoke for draft gears comprising top and bottom members connected at their rearward ends and provided with integral side walls at their forward ends to prevent 10 spreading of the top and bottom members, said top member being provided with an integral lug to receive draw bar stresses, the forward end of said bottom member being depressed and provided with an abutment 15 spaced sufficiently from the lug on said top member to allow the butt of the draw bar to be inserted endwise, and a member capable of swinging movement in the depressed portion of said bottom member and provided 20 with means to receive draw bar stresses and to transfer them to said abutment.

10. A yoke for draft gears comprising top and bottom members connected at their rearward ends and provided with integral side 25 walls at their forward ends to prevent spreading of the top and bottom members, said top member being provided with an integral lug to receive draw bar stresses, the forward end of said bottom member being 30 depressed and provided with an abutment spaced sufficiently from the lug on said top member to allow the butt of the draw bar to be inserted endwise, a member capable of swinging movement in the depressed portion 35 of said bottom member and provided with means to receive draw bar stresses and to transfer them to said abutment, and lugs on said side walls above said abutment to assist the latter in receiving draw bar stresses. 40

11. A yoke provided with a hooded forward end within which is adapted to be received a shouldered draw bar butt, said yoke being provided with means arranged to engage the upper shoulder of a draw bar butt, 45 and devices, coöperable with the lower shoulder of a draw bar butt, for detachably locking the yoke to a draw bar, said devices including a shouldered block engageable with the lower shoulder of a draw bar butt, said 50 block being removable through an opening in the bottom of the hood, and a detachable key member for supporting the front end of the block in operative position, the rear 55 end of said block being loosely secured on a shelf formed on the yoke.

12. A yoke provided with a hooded forward end within which is adapted to be received a shouldered draw bar butt, said yoke being provided with means arranged to engage the upper shoulder of a draw bar 60 butt, and devices, coöperable with the lower shoulder of a draw bar butt, for detachably locking the yoke to a draw bar, said devices including a shouldered block removable through an opening in the bottom of said 65 hooded end, the rear end of said block being loosely supported on a shoulder formed in the yoke, said rear end of the block having a curved upper surface adapting it to act as a cam to lift the draw bar into place when 70 the block is moved to operative position.

13. A cast yoke having a hooded forward end, the latter having an integral shoulder across the top thereof and an opening in the bottom wall, and a locking block insertible 75 through said opening, said block having an upstanding shoulder arranged to engage with the lower shoulder of a draw bar, the rear end of said block being detachably supported on a ledge formed in the lower 80 portion of the hood, the side walls of the hood being provided with shoulders on the inner faces thereof against which said block bears in draft.

14. A yoke of the character described having a hooded forward end, the latter having two shoulders on the inner side of the upper wall thereof and between which a draw bar butt is adapted to be received, the hood also having an integral shoulder at the bottom thereof against which the rear face of the draw bar butt is adapted to bear in buffering, said hood having an opening in the bottom wall, a shouldered block insertible 85 and removable through said opening, and a detachable key for supporting said block in operative position. 90

15. A cast steel yoke for draft riggings having a hooded forward end, the bottom wall of said hooded end being provided with 100 an enlarged opening therethrough, said yoke being also provided with a transversely extending ledge at the rear end of said opening on which is adapted to rest the inner end of a removable locking block. 105

In witness that I claim the foregoing I have hereunto subscribed my name this 24th day of January, 1916.

CHARLES E. DATH.
